UNITED STATES PATENT OFFICE.

FANNIE J. BOOZE, OF SPRINGWOOD, VIRGINIA.

LOOM.

SPECIFICATION forming part of Letters Patent No. 688,500, dated December 10, 1901.

Application filed August 27, 1901. Serial No. 73,428. (No model.)

To all whom it may concern:

Be it known that I, FANNIE J. BOOZE, a citizen of the United States, residing at Springwood, in the county of Botetourt and State of 5 Virginia, have invented certain new and useful Improvements in Looms, of which the following is a specification.

My invention particularly relates to that class of looms known as "hand-looms" and 10 which are especially adapted for domestic use in making rag carpets, rugs, and other like fabrics of relatively coarse material.

The object of my invention is to provide a loom of this general character which shall be 15 simple in construction, easily operated, and capable of being folded into a small space when not in use or opened to hold the parts in proper position when used.

In carrying out my invention I provide a 20 folding frame adapted to carry the warp-beam, the breast-beam, and the cloth-beam, while the heddle-frame is hinged to the folding frame in such manner that it may be folded when the main frame of the loom is 25 folded, and it can also be moved back and forth to beat up the filling as fast as inserted.

In the accompanying drawings, illustrating 30 my invention, Figure 1 is a perspective view of my improved loom. Fig. 2 shows a longitudinal central section through the loom. Fig. 3 is a side view of the loom when folded. Fig. 4 is a detail view showing the manner in which the heddle is moved up and down. Fig. 5 is a detail view showing the manner of 35 connecting the cloth to the cloth-beam, and Fig. 6 is a detail view showing the manner in which the heddle operates.

The main frame of the loom consists of frame-beams A, connected by cross-pieces a 40 a', and frame-beams B, connected by cross-pieces b b'. The frame-beams A and B are hinged together at x, and when open the frame-beams A rest against the cross-piece a, as indicated in Fig. 2. Set-screws or bolts 45 with thumb-nuts are employed for hinging together the frame-beams A and B, so that when the parts are folded, as in Fig. 3, they may be tightly clamped together. They may also be tightly clamped together when opened, 50 as in Fig. 1.

The beams A and B are held firmly apart by means of dogs D, hinged to the beams B

above the pivots x and engaging notches d in the beams A. The warp-beam E is mounted in bearings on the upper ends of the frame-beams A. The breast-beam F is secured to the upper ends of the frame-beams B, and the cloth-beam G is arranged in bearings on the frame-beams B just below the breast-beam F. The warp-beam is free to turn in 60 its bearings, but may be held in any desired position by means of a pawl-and-ratchet device e. The cloth-beam may be turned to the desired extent and held by means of a pawl-and-ratchet device g. The cloth-beam is preferably provided with handles g' for turning it. 65

The heddle-frame consists of two bars H, hinged at h to the outside of the frame-beams A above the pivots x. The heddles are formed in a thin plate or piece of wood J, which extends across the loom-frame and projects into vertical recesses in the heddle-frames H. This heddle-board is free to move vertically in the guides formed by the recesses. It is pressed upwardly by means of springs K, and 70 when the heddle-board is moved downward it is moved against the force of these springs. The heddle-board is moved downwardly by hand, the operator taking hold of any part of any board between the frames H. The heddle-board is provided with a series of vertical slots j, through which one set of the warp-threads is passed, while the unslotted portions of the board between the slots are provided with perforations j', through which the other set of 75 warps passes. These perforations are located about midway between the ends of the slots. As the heddle-board is moved up and down the warp-threads which extend through the slots are not raised or lowered; but the warp-threads which extend through the perforations j' are raised and lowered, and by this 80 means the sheds are formed. The warp-threads X are attached to a rod L, which is in turn attached to the warp-beam E by means 85 of hooks or other similar devices l, which permit of the rod being removed and replaced when desired. When the warp-threads are thus attached to the rod and the rod is attached to the warp-beam, the warp-beam may 90 be rolled up with the rod to the desired extent and the warp-threads may be let out when desired. The opposite ends of the 95 warp-threads are in like manner attached to 100

a rod M, which is in turn attached to the cloth-beam by means of hooks, staples, or similar devices m. This rod may be also attached to the cloth-beam by means of cords N, which 5 may be wound upon the cloth-beam in order to draw the rod tightly against the beam, and then the warp-threads may be wound up around the cloth-beam and also around the rod.

10 The filling is inserted by means of a shuttle O, which is passed back and forth through the sheds as they are formed in the usual way. The filling may be beaten up by the heddle-board, which may be moved with the 15 heddle-frame toward and from the breast-beam, or the shuttle may be inserted in the shed and left there while the heddle-frame is moved toward the breast-beam, causing the shuttle to beat up the filling.

20 My improved loom may be manufactured at small expense and may be folded to occupy but a small space, while affording ample room to weave fabrics of various sizes. The frame-sections of the loom and the heddle-frame are 25 so connected with each other that they may be folded without taking any of the mechanism apart.

The frame-beams B may be so folded as to lie parallel with the frame-beams A, the heddle-board being raised sufficiently high for this 30 purpose. The heddle-frames being hinged on the outside of the beams A may be folded inward until they are nearly parallel with the frame-beams A or until the heddle-board 35 abuts against the frame-beams A.

I claim as my invention—

1. The combination of the frame-beams hinged together, the warp-beam carried at the 40 upper ends of the frame-beams on the one side, the breast-beam and cloth-beam carried at the upper ends of the frame-beams on the

opposite side, and the heddle-carrying frame hinged to the frame-beams and adapted to fold therewith.

2. The combination of two frame-beams 45 carrying at their upper ends the warp-beam, two other frame-beams hinged to the first-mentioned frame-beams, and carrying at their upper ends the breast-beam and cloth-beam, the heddle-frame hinged to the frame-beams 50 above their hinge connection with each other, a heddle-board moving vertically in guides in the heddle-frame, and springs for moving the heddle in one direction.

3. The combination of the folding loom-frame, the folding heddle-frame, and devices 55 for holding the parts of the folding frame open when desired.

4. The combination of the frame-beams carrying the warp-beam, the frame-beams 60 carrying the cloth-beam hinged to the inside of the first-mentioned frame-beams, devices for clamping the two sets of beams together at their hinge connection, and a heddle-frame hinged to the outside of the first-mentioned 65 frame-beams.

5. The combination of the folding loom-frame, the folding heddle-frame, devices for holding the sections of the loom-frame open 70 when desired, the warp-beam, the rod to which the warps are attached, and which is in turn attached to the warp-beam, the cloth-beam, and the rod to which the warps are attached, and which is in turn attached to the cloth-beam.

In testimony whereof I have hereunto subscribed my name.

75 FANNIE J. BOOZE.
